BACK HEIGHT CONTROL GAGE

Basil E. Chadbourne, Lynn, Mass., assignor to Duchess Footwear Corp., Salem, Mass., a corporation of Massachusetts

Filed Feb. 18, 1965, Ser. No. 433,572

3 Claims. (Cl. 12—141)

This invention relates to shoe construction and more particularly comprises a new and improved mold for accurately controlling the height of a shoe upper at the counter region.

In the manufacture of cement shoes, stitched uppers are sometimes subjected to a molding operation to shape the counter portion of the upper before lasting. One object of the molding operation is to form the counter region so that the height of the back of the upper conforms to the height prescribed for the particular shoe size into which the upper is to be formed. At the present time molding machines include no special fixtures to assist the operator in placing the upper about the mold in the proper position to accurately control the height of the back, and therefore, the control or accuracy of the back height is left completely to the experience of the operator who places the upper about the mold. Through experience operators acquire some skill in controlling the dimension of the back height but placement of the upper on the mold is judged by eye and feel. Without some gage to control the position of the upper on the mold it will be appreciated that it is impossible to produce consistently accurate results, particularly as the back height varies approximately $\frac{1}{16}$ " between consecutive whole sizes. For example, a size 4 women's cemented shoe may have a back height of $2\frac{3}{32}$ " while the same style shoe in size 5 will have a back height of $2\frac{5}{32}$ ".

One important object of this invention is to provide a mold for shaping the counter portion of an upper, which will accurately control the back height of the upper when forming the counter.

A more specific object of this invention is to provide in a mold for forming shoe counters a gage which will enable an operator to place a shoe upper in proper position on the mold so as to achieve the proper back height when the mold shapes the counter portion of the upper.

Another important object of this invention is to provide a mold for the counter portion of shoe uppers, which receives interchangeable gages to provide stops at the proper location to determine the back height for shoes of different sizes.

Yet another important object of this invention is to provide a mold for shaping the counter portion of shoe uppers, which may be altered in just a few seconds to make the mold suitable for forming counters of a different size.

To accomplish these and other objects, this invention includes a mold having a slot provided in the back seam region of the mold, which is adapted to receive one of a number of different gages. Each gage carries a projection that extends rearwardly from the mold when the gage is positioned in the slot, and the projection serves as a stop to locate the top line of the shoe upper on the mold. By locating the position of the top line of the upper, the height of the back of the shoe is controlled when the lasting margin is folded over the mold.

These and other objects and features of this invention along with its incident advantages will be better understood and appreciated from the following detailed description of one embodiment thereof, selected for purposes of illustration and shown in the accompanying drawing, in which:

FIG. 1 is a side view of a mold constructed in accordance with this invention;

FIG. 2 is a top view of the mold shown in FIG. 1;

2

FIG. 3 is a rear view of the mold shown in FIG. 1;

FIG. 4 is a side view of the gage in the mold shown in FIGS. 1-3;

FIG. 5 is a side view of another gage interchangeable with that shown in FIG. 4 in the mold; and

FIG. 6 is a side view similar to FIG. 5 and showing an upper on the mold.

The mold 10 shown in FIGS. 1-3 is generally shaped to conform to the counter portion of a shoe upper and is shown mounted in an inverted position on a base plate 12. The base 12 secured to the collar portion 14 of the mold 10 may be formed as an integral part of the mold body 10 or alternatively may be secured thereto by machine screws or other fastening means. The base 12 is provided to secure the mold body 10 in the molding machine in which the molding operation is performed. Typically, the mold may be used in such machines as a Lauretti Molder used to form the counter portion of uppers.

The mold body 10 has a flat upper surface 16 which conforms to the bottom of the shoe, and on the surface 16 the overlusted margins of the upper are folded so as to shape the counter portion and control the back height.

A slot 18 is provided in the body 10 at the back seam region of the body, which slot extends from the upper surface 16 of the body to a point immediately above the base 12. The slot 18 is relatively narrow as shown in FIGS. 2 and 3, but is relatively deep as measured in a horizontal direction from the back of the body. A recess 20 in the upper surface 16 of the mold forms a continuation of the slot 18. The recess 20 extends forwardly from the slot 18 to a point approximately in the middle of the heel portion of the body. The slot 18 and recess 20 lie in a vertical plane which bisects the body 10 in a longitudinal direction.

A gage 22 shown separately in FIG. 4 is mounted in the body with its vertical leg 24 disposed in the slot 18 and its horizontal arm 26 disposed in the recess 20. The width of the gage 22 is slightly smaller than the width of the slot and recess so that the gage fits easily within them. The back edge 28 of the leg 24 is of the same curvature as the back of an upper at the seam region, and the edge 28 merges smoothly into the body shape. Similarly, the upper edge 30 of the arm 26 is flat so that the upper edge lies in the plane of the upper surface 16 of the body 10. Thus, when the gage 22 is disposed within the body, the body has an unbroken surface which is the same shape as the body of a conventional mold.

A detent 32 is formed at the forward edge 34 of the arm 26 and cooperates with a hold down spring 36 having a hooked end 38 to yieldably retain the gage in place in the body. The spring 36 is removably secured to the surface 16 of the body by a machine screw 40.

The gage shown in FIGS. 1 and 4 is designed to be used to form the counter portion of a size 4 shoe. In one style of women's shoes, the back height of a size 4 is normally $2\frac{3}{32}$ ", and to establish this height in the counter portion of the shoe upper a projection 42 is provided on and forms an integral part of the gage 22. The projection 42 serves as a stop that extends rearwardly from the body 10 in the plane of the back seam region when the gage 22 is mounted in the body, and the projection is positioned to engage the top line of a shoe to limit the extent to which the upper may be positioned down over the body. When the top line of the upper engages the projection 42 the lasting margins of the counter portion are wiped over the surface 16 the resulting upper is formed with a back height equal to the distance between the edge 30 of the horizontal arm 26 of the gage and the upper surface 44 of the projection 42.

A gripping device in the form of a small rectangular plate 46 is secured to the edge 30 of the arm 26, and the

plate 46 has a hole 48 in its center through which a hook may be inserted to lift the gage 22 from the body. The plate 46 is particularly important when the gage is used in a mold which becomes hot during use. In conventional molding machines to form the counter portion of the upper heat is applied to the body or male portion of the mold by heating coils embedded therein or heat is indirectly transferred to the body from the female mold which itself may be heated. Regardless of how heat is actually introduced into the body 10, it does in fact become hot and the hole 48 in the plate 46 allows the operator to insert a hook-like tool to pull the gage 22 from the mold. With the gage removed, another gage may be placed in the body to mold shoes of a different size on the machine.

The gage 50 shown in FIG. 5 is the same as the gage 22 of FIG. 4 and includes a vertical leg 52 and a horizontal arm 54. The only difference between the gages 22 and 50 lies in the positions of the projection 42 of gage 22 and projection 56 of gage 50. The gage 50 is designed to be used to form size 10 shoes, and the distance between the upper surface 58 of the arm 54 and the upper surface 60 of the projection is $2\frac{1}{2}\frac{1}{2}$; that is $1\frac{1}{2}\frac{1}{2}$ greater than the comparable distance in the gage for a size 4 shoe. It is apparent that merely by replacing gage 22 with gage 50 the body 10 is suitable for molding the counter portion of a shoe upper and providing it with the proper back height for a size 10 shoe.

In FIG. 6 the manner in which the body 10 with its gage is used as illustrated. It will be noted in that figure that the body 10 is shown with a portion of an upper 62 mounted on it. The top line 64 of the upper 62 is shown to engage the upper surface 44 of the projection 42 of the gage 22 mounted in the body. It is apparent that when the operator places the upper over the body 10 and brings the top line 64 of the upper into engagement with the projection, the height "h" of the back of the upper is made to conform to the distance between the upper surface 16 of the body and the upper surface of the projection. When the upper is molded about the mold body 10 in cooperation with a female mold (not shown) which folds the lasting margin 66 of the upper over the edge of the body, onto the top surface 16, the back height is set. During subsequent shoe operations when the upper is assembled on a last, the height of the back is preset for the operator and the shoe will remain in the shape determined during the molding operation.

From the foregoing description those skilled in the art will appreciate that numerous modifications may be made of this invention without departing from its spirit. Therefore, it is not intended to limit the breadth of this invention to the specific embodiment illustrated and described. Rather, it is intended that the scope of this invention be determined by the appended claims and their equivalents.

What is claimed is:

1. Means for controlling the back height of the counter portion of a shoe upper comprising
  - a mold body shaped to form the counter portion of a shoe upper and adapted to be oriented to carry the upper in an inverted position,
  - a slot provided in the back seam region of the mold body extending vertically from the top surface of the inverted body downwardly substantially to the bottom of the body,
  - a recess provided in the upper surface of the body and extending forwardly from the top of the slot,

2. Means for controlling the back height of a counter of a shoe upper comprising,
  - a mold body shaped to conform to the counter portion of a shoe upper with the sole portion of the body disposed uppermost,
  - a slot provided in the body extending from the sole portion downwardly along the back seam region of the body to a point below the top line region of an upper placed in an inverted position over the body,
  - a recess provided in the body along the top surface thereof and forming a continuation of the slot,
  - a generally L-shaped gage sized to be mountable on the body with a leg of the gage in the slot and the base of the gage in the recess,
  - a flange provided in the free end of the base of the gage and extending upwardly from the top surface of the body when the gage is mounted in said body,
  - a spring secured to the upper surface of the body and engaging the flange to releasably retain the gage in the body,
  - a gripping member secured to the upper surface of the base of the gage and adapted to be engaged by a hook-like member to remove the gage from the slot and recess in the body,
  - and a projection carried on the leg of the gage and located a prescribed distance below the top surface of the body for engaging the top line of an upper when formed about the body to form a counter of preselected height.
3. Means for controlling the back height of a counter portion of a shoe upper comprising,
  - a mold body shaped to form the counter portion of a shoe upper and adapted to be oriented to carry the upper in an inverted position,
  - slot means provided in the back seam region of the mold body extending vertically from the top surface of the inverted body downwardly substantially to the bottom of the body,
  - a gage conforming in shape to the slot means and removably mounted in the slot means to provide the counter forming portion of the body with a smooth continuous molding surface,
  - a rearwardly extending projection carried by the gage and extending from the body in the back seam region for engaging the top line of the counter portion of an upper placed on the body,
  - and engaging means connected to the gage for removing the gage from the slot means.
